PILE CONSTRUCTION

Karl Nolte, Dortmund, Germany, assignor to
 Dortmund-Hörder Hüttenverein Aktiengesellschaft, Dortmund, Germany

Application March 15, 1934, Serial No. 715,580
 In Germany March 21, 1933

3 Claims. (Cl. 61—61)

Walls formed of piles of I- or H-section are known in which the flanges of the piles are connected together by I-shaped locking members inserted between the ends of the flanges that have been suitably thickened to receive them. 5 So long as straight walls or curves of large radius are to be produced, no special difficulties are involved. The difficulties encountered are, however, great when a circular or similar wall is to be produced from such sections, particularly 10 if the radius is very small. To avoid such difficulties it has been proposed to arrange so-called compensating members on the inside and on the outside, the compensation being made either 15 after each pile or after every second pile. Such compensating members have however great disadvantages as they are likely to increase the difficulty of ramming to such an extent that it is not possible to retain the circular or curved formation. 20

According to the invention these difficulties are avoided in very simple manner by omitting the locking connections on one side of the wall and by completely or partly bending or curving back the free flanges thus produced; the free flanges altogether or alternately may be partly or completely bent or curved back outwardly or inwardly, and at one end, or at both ends. Apart from the fact that by this means it is possible to dispense with the compensating members it has been found that the absence of the locking connections on the inside of the curves involves no disadvantage but on the contrary is an advantage. 30

The accompanying drawings show several examples of pile construction according to the invention in cross-section.

Figures 1 to 10 show diagrammatically the circular formation, which is illustrated for the sake of clarity with an exceedingly small radius, while Figures 11 to 13 show three constructions with the details enlarged.

According to Figure 1 of the drawings, a section of the curved pile wall is made up of two girders *a* and *b* of different shapes, which at *c* are provided with locking connections, whereby they are held together. In dimensions the I- or H-sections are all alike except that the I- or H-section *b* is produced from an I- or H-section

5 by providing the flange *d* at an inclination to the web *e*, which operation involves little difficulty. It is furthermore possible to produce the curve solely from I- or H-sections such as *b*, the advantage of which is that the angle formed by the flange *d* and the web *e* is smaller.

In Figure 3 the flanges of each second I- or H-section *h* are bent inwardly.

Figure 4 shows I- or H-sections *g* alternating with I- or H-sections *h*, the flanges being bent 10 alternately inwardly and outwardly.

Figure 5 is similar to Figure 4 except that only the ends of the flanges are bent.

Figures 6 to 10 correspond to Figures 1 to 5 except that the sharp-bent-back portions are 15 formed as curves.

Figure 11 illustrates on an enlarged scale a section of the wall as shown in Figure 1. The I- or H-sections *a* are in this case connected to the I- or H-sections *b* by I-shaped locking 20 members *f* provided on the outside of the curve and inserted between the thickened ends of the flanges.

Figure 12 illustrates a section on an enlarged scale of the pile wall illustrated in Figure 4, while 25 Figure 13 is a similar view of a section of the pile wall illustrated in Figure 10.

I claim:

1. A curved pile wall made up of I- or H-sections, which are held together by locking 30 members on the outer side only of the curve, characterized in that the free flanges of the I- or H-sections on the inside of the curve have their adjacent edges overlapping and offset with relation to each other so that they do not impede 35 each other in the ramming operation.

2. A curved pile wall made up of I- or H-sections, which are held together by locking members on the outer side of the curve, characterized in that the flanges of the alternate pairs of I- or 40 H-sections are inclined, bent or curved in the inward and outward directions respectively.

3. A curved pile wall made up of I- or H-sections, which are held together by locking members on the outer side of the curve, characterized 45 in that one flange of alternate I- or H-section is inclined, bent or curved inwardly and the other flange outwardly.

KARL NOLTE.
